UNITED STATES PATENT OFFICE.

ARTHUR J. SUHM AND EDGAR A. SUHM, OF MILWAUKEE, WISCONSIN.

BOTTLE-HOLDER.

No. 856,431.

Specification of Letters Patent.

Patented June 11, 1907.

Application filed October 12, 1906. Serial No. 338,559.

To all whom it may concern:

Be it known that we, ARTHUR J. SUHM and EDGAR A. SUHM, citizens of the United States, residing at Milwaukee, county of Milwaukee 5 and State of Wisconsin, have invented new and useful Improvements in Bottle-Holders, of which the following is a specification.

Our invention relates to improvements in bottle holders for bottle washing and soaking 10 machines.

The object of our invention is to provide an inexpensive and durable form of holder which will support the bottle securely in an inverted position and in which the bottle will 15 be protected from contact with rigid metallic parts, the holder having a certain degree of flexibility which permits the bottle to adjust itself into a secure position, without sufficient resilient reaction to displace the bottle from 20 such position after it is once adjusted therein.

In the following description reference is had to the accompanying drawings, in which,

Figure 1 is a side view of my invention 25 showing the meeting side edges of the bottle holding shell connected by a retaining piece. Fig. 2 is a top view of the same. Fig. 3 is a side view showing a retaining piece independent of the connection of the meeting 30 edges. Fig. 4 is a side view showing the shell as it is held in position by stitches which embrace the frame bars. Fig. 5 is a vertical sectional view drawn to a plane, cutting the seam.

Like parts are identified by the same reference characters throughout the several views.

An open and downwardly tapered metallic frame is composed of top and bottom rings 1 40 and 2 and connecting bars 3 with a projecting shoulder 5 adapted to facilitate its attachment to a suitable support. This frame supports a non-metallic shell 6 in the form of an inverted truncated cone, open at both 45 ends, and having an outwardly curved or rolled upper margin 7 which embraces the upper frame ring 1. From this rolled margin the shell extends downwardly through the rings 1 and 2. This shell is preferably 50 formed of leather, although other fibrous material of a comparatively inelastic nature such as felt, may be employed, if desired. The meeting edges of the strip or sheet of material from which the shell is formed, are 55 preferably held together by an exterior connecting piece 10 which is stitched or riveted

to the shell at each side of the seam, near the upper end, and the shell is adjusted to the frame in such a position that the connecting piece engages the lower edge, of the ring 1 60 between the connecting bars 3 of the frame rings, and prevents the shell from being withdrawn with the bottle.

The location of the piece 10 between the connecting bars 3 permits a sufficient yielding of the shell wall at this point to prevent damage to the bottles, even where metal rivets are used.

If desired, the meeting edges of the shell may be otherwise secured together by ordinary lacing or by a metallic fastening of sheet metal as illustrated in Fig. 3. These metallic fastenings are in common use for fastening leather strips together and are provided with prongs (not shown) which are embedded and 70 clenched in the leather, and the shell held in position by a retaining piece 12 similar to the connecting piece 10 but located at one side of the seam. The shell may also be held in position by stitching 13 (Fig. 4) extending over 75 the frame bars 3 and through the wall of the shell in the intervening spaces near the center of such spaces where sufficient yielding is permitted to compensate for the projection of the lace on the interior shell surface. 80

Bottle holders formed in this manner may be subjected to the action of either hot or cold water and when wet, as is the case while in use, they are soft and flexible, without material resiliency. The bottles may therefore 90 be dropped into them with the utmost carelessness without risk of injury.

The outwardly rolled upper margin of the shell may be secured by pressing the shell in a die after dampening the material of which 95 it is composed. Leather shells made in this manner retain their form through long periods of use. The margin 7 should be rolled outwardly and the edge turned downwardly so as to completely cover the upper portion 100 of the ring 1. The turned down margin 7 should also be secured by stitches or fastenings 14 at the meeting edges to prevent it from straightening out.

Having thus described our invention what 105 we claim as new and desire to secure by Letters Patent is,

1. A bottle holder comprising a downwardly tapered metallic frame having side openings and a tapered shell of comparatively 110 inelastic but yielding fibrous material, extending through the frame with its upper

margin curved outwardly and downwardly over the upper end of the frame and its lower margin extending below the frame; said shell having a retaining member connected therewith in the frame opening.

2. A bottle holder comprising a downwardly tapered metallic frame having side openings and a tapered shell of comparatively inelastic but yielding fibrous material, extending through the frame with its upper margin curved outwardly and downwardly over the upper end of the frame and its lower margin extending below the frame; said shell having a retaining member connected therewith in the frame opening, and serving also as a connecting member for the meeting side edges of the shell.

3. A bottle holder comprising a downwardly tapered metallic frame having side

openings and a tapered shell of comparatively inelastic but yielding fibrous material, extending through the frame with its upper margin curved outwardly and downwardly over the upper end of the frame and its lower margin extending below the frame; said shell having a retaining member connected therewith in the frame opening, and serving also as a connecting member for the meeting side edges of the shell, the turned down edges of the upper margin being also secured together at the meeting edges.

In testimony whereof we affix our signature in the presence of two witnesses.

ARTHUR J. SUHM.
EDGAR A. SUHM.
